STORM WINDOW

William P. Collins, Toledo, Ohio, assignor to
Libbey-Owens-Ford Glass Company, Toledo,
Ohio, a corporation of Ohio

Application April 28, 1941, Serial No. 390,669

1 Claim. (Cl. 20—52.1)

The present invention relates to improvements in storm windows.

It has been heretofore customary to make use in the wintertime of supplemental storm windows which are detachably secured to the regular permanent windows, usually outside thereof, by means of screws, hangers or other fastening devices. The ordinary storm windows are, however, relatively heavy and quite cumbersome to handle, as well as being inconvenient and time consuming to hang and take down. Furthermore, when the storm windows are taken down during the summertime considerable space is required for the storage thereof. In addition, during the summertime the storm windows are apt to become quite dirty as well as being subjected to the liability of being knocked about and broken.

It is the aim of this invention to avoid the above objectionable features incident to the use of the ordinary removable storm windows by providing a so-called "built-in" storm window which is permanently mounted in such a manner as to eliminate the necessity of removal and replacement thereof at different seasons of the year while, at the same time, being readily removable from an operative to an inoperative position.

Another important object of the invention is the provision of a built-in storm window of the above character which is slidably associated with the regular window in such a manner that it can be lowered into a compartment or well located beneath the window opening, during the summertime, where it will be out of the way as well as being protected from the weather and against the liability of being broken or damaged during the period of the year it is not in use.

A further important object of the invention is the provision of a built-in storm window of the above character embodying novel means for mounting the same including hinged plate members movable from a vertical position to a horizontal position serving as guides for the storm window when arranged in a vertical position and as a cover for the compartment or well beneath the window opening when arranged in a horizontal position.

A still further important object of the invention is the provision of a built-in storm window of the above character including novel means serving to support the storm window in operative position at its lower edge and for also maintaining the plate members in closed horizontal position when the storm window is lowered into

inoperative position within the compartment or well.

Other objects and advantages of the invention will become more apparent during the course of the following description when taken in connection with the accompanying drawing.

In the drawing wherein like numerals are employed to designate like parts throughout the same:

10 Fig. 1 is a vertical transverse section through a regular permanent window having associated therewith a built-in storm window provided by the present invention;

15 Fig. 2 is a vertical section taken substantially on line 2—2 of Fig. 1 and showing the storm window in lowered position;

Fig. 3 is a horizontal section taken substantially on line 3—3 of Fig. 1;

20 Fig. 4 is a vertical section taken substantially on line 4—4 of Fig. 2; and

Fig. 5 is a section taken substantially on line 5—5 of Fig. 4.

With reference now to the drawing, 10 generally indicates the wall of a building having an opening in which is mounted the usual double-hung window 11 comprising the upper and lower relatively slidable sashes 12 and 13 glazed with the panes of glass 14 and 15. Although there has been shown a regular permanent window of the double-hung type, it is obvious that this invention may be employed, if desired, with a window having a single pane of glass.

Also mounted within the window opening, preferably inwardly of the regular window 11, is the improved "built-in" storm window 16 comprising generally a rectangular frame 17 glazed with the pane of glass 18. Formed in the wall 10 of the building beneath the window opening and in alignment with the storm window 16 is a rectangular compartment or well 19 adapted to receive the storm window therein when not in use. The upper rail of the storm window frame is preferably provided with a hand hold or the like 20 to facilitate the raising and lowering of said window. During the wintertime, the window is raised to position opposite the regular window as shown in full lines in Fig. 1, whereas during the summertime, it is lowered into the compartment or well 19 as indicated by the broken lines. In this way, the storm window is permanently associated with the building, in that it need not be entirely removed from the building although it can be easily and conveniently moved out of operative position.

This arrangement obviously results in many

practical advantages such as the saving of the time and labor required to remove and replace the ordinary storm windows at different seasons of the year; the elimination of storage space for the storm windows during the summertime, as well as obviating the liability of breakage of or damage to the windows when removed from the building. With this arrangement, the use of screws, hangers or other fastening devices is also eliminated. Moreover, the washing of the outside of the regular windows during the winter can be greatly facilitated by temporarily lowering the storm windows 16 into the compartments 19. Likewise, if desired, the storm windows may be temporarily lowered during periods of unseasonably warm weather, especially during the spring of the year when sudden and drastic changes in temperature are encountered.

The storm window construction herein provided also includes the provision of means serving not only as a cover for the upper end of the compartment or well 19 when the storm window is lowered therein, but also acting as guides to facilitate the raising of the storm window into operative position and for maintaining said window in proper position relative to the regular window 11. Such means comprises a pair of substantially flat plate members 21 and 22 hinged at their outer ends as at 23 and 24 respectively within recesses 25 and 26 in the wall 10 of the building at opposite sides of the window opening. The hinges 23 and 24 are preferably of spring construction acting to normally swing the plate members 21 and 22 upwardly into vertical position as indicated in broken lines in Fig. 2.

The plate members 21 and 22 are provided upon their inner surface with longitudinally extending tongues 27, while the side rails of the storm window frame 17 are provided with complementary grooves 28 for receiving said tongues therein. With this arrangement, when the storm window is in use, the plate members are disposed in a vertical position and lie flat against the inner sides of the wall of the building, or against the window casing which may be arranged within the window opening. The tongues 27 are then received within the grooves 28 in the frame of the storm window as clearly shown in Fig. 3 and serve to maintain the window in place. If desired, fixed guides 29 may be provided above and in alignment with the upper ends of the movable plate members.

When the storm window 16 has been raised into operative position, it is supported in such position at its lower edge by means of a latch

member 30 slidable horizontally through an opening 31 in the front wall of the compartment 10 and having its rear end received within a recess 32 in the rear wall of said compartment. The forward end of the latch member 30 may be provided with a hand gripping portion 33 to facilitate actuation thereof. When it is desired to lower the storm window into the compartment 16, the latch 30 is simply drawn forwardly out of the path of downward movement of the storm window 16. After the storm window has been lowered into the compartment 16, the plate members 21 and 22 are swung downwardly to horizontal position as indicated in Fig. 2 where they serve as a cover for the upper end of said compartment. The latch 30 may also be used to secure the plate members 21 and 22 in horizontal position by sliding it rearwardly into mating grooves 34 and 35 formed in the end edges of the tongues 27 of said plate members as best shown in Fig. 5. If desired, suitable means may be provided to counterbalance the storm window to facilitate the raising thereof.

It is to be understood that the form of the invention herewith shown and described is to be taken as the preferred embodiment of the same, and that various changes in the shape, size and arrangement of parts may be resorted to without departing from the spirit of the invention or the scope of the subjoined claim.

I claim:

In a window construction, the combination with the wall of a building having an opening therein for receiving a window and being further provided with a compartment beneath said window opening, of a window mounted within said window opening and movable vertically from an operative position into an inoperative position within said compartment, plate members pivotally mounted at their outer ends and adapted to swing from a horizontal position to a vertical position, said plate members forming a cover for said compartment when in a horizontal position and guides for said window when in a vertical position, the said plate members being further provided with longitudinally extending tongues adapted to be received within grooves in the sides of the window for guiding the latter and maintaining it in operative position, and a horizontally slidable latch serving to support the said window at its lower edge when the latter is in operative position and for securing the said plate members in horizontal position when said window is received within said compartment.

WILLIAM P. COLLINS.
